UNITED STATES PATENT OFFICE.

LEONARD ATWOOD, OF ORANGE, MASSACHUSETTS, ASSIGNOR TO THE NEW HOME SEWING MACHINE COMPANY, OF ORANGE, MASSACHUSETTS, A CORPORATION OF MASSACHUSETTS.

SEWING-MACHINE TABLE.

Application filed June 5, 1922. Serial No. 566,018.

To all whom it may concern:

Be it known that I, LEONARD Atwood, a citizen of the United States, residing at Orange, in the county of Franklin and State of Massachusetts, have invented certain new and useful Improvements in Sewing-Machine Tables, of which the following is a specification.

Heretofore attempts have been made for raising the head of a drop head sewing machine by means of a wire cable attached to the head frame and drop leaf, so that when the latter is folded from its extension position down upon the top of the machine the drop head will automatically descend to its housed position. It has been found, however, that such cables will elongate in use to such an extent that when the leaf is swung over from its housing position to its usable position, the drop head will not be brought snugly up into place, but will sag down therefrom.

It is also found that when the head is brought up into place, the downward strain given thereto by the belt which takes its power from the fly wheel beneath will cause the head to shake and tremble in a manner most detrimental to good sewing.

To overcome these defects, I provide a chain in place of a cable, and so connect the same with the drop head frame that the strain thereon is practically uniform, and there can be no stretching or sagging, the preferable connection for the chain comprising a pivoted lever arm supported by the machine frame, and an antifriction roller carried by the head frame and resting upon the lever arm.

For preventing the shaking and trembling of the drop head frame, I provide a locking bar running the entire length of the drop head frame and longitudinally moved by the extension leaf to lock the end of the drop frame which is adjacent the belt so that the frame cannot vibrate thereat.

In the drawings forming part of this specification, Fig. 1 is a sectional elevation of a sewing machine provided with the embodiments of my invention. Fig. 2 is a plan view of portions of the machine. Fig. 3 is a sectional detail view. Fig. 4 is another plan view showing in dotted lines the anti-shake rod. Fig. 5 is a side sectional elevation of the same. Fig. 6 is a side sectional

elevation of the same but with its extension leaf partially lifted.

The reference numeral 1 designates the top of a sewing machine; 2 its drop frame upon which the machine head is mounted, and 3 is the extension leaf. To the framework 4 of the machine cabinet is pivoted at one end 5 a lever arm 6 which is yieldingly pressed upward by a helical spring 7, and upon this lever arm rests an antifriction roll 9 carried by the drop frame 2. When the drop frame is permitted to swing downward to the housing position desired for its machine head, the roll 9 travels to the extremity of the lever arm 6, and, since the drop frame is to be drawn up into position by a pull upon the lever arm, the upper surface of the free end of the latter is given a concave curve in order that the upward pull applied to the lever arm will the more easily force the roll along the same. In other words, the curvature gives a cam-action to the roll. This curve 10 is needed only at the section of the lever arm traversed by the roll, and acts to equalize the lifting strain given by the head to the lever.

For the actuation of the lever arm 6 by the movement of the extension leaf 3 from its closed or housed position to its used position, I attach a chain 11 to the arm and leaf as shown in Fig. 3, a metallic race-way 12 being provided over which the chain slides. In this figure, the extension leaf 3 is represented as nearly vertical, and the drop frame 2 as in its uppermost position. Hence the chain 11 must be shown as broken in order to indicate that these two positions are not simultaneously possible. The lower end of the chain 11 is attached to a screw eye 14 having a nut 15 provided with a curved surface fitting a concave seat in the lever arm 6 for the purpose of allowing angular variations in the chain's direction of pull.

Since the chain 11 through the lever and roll 6, 9 acts upon the drop frame 2 at its end farthest from the actuating pulley 19 of the sewing machine head, the opposite end and the one which receives the pull of the belt upon this pulley, is insufficiently supported and will consequently become liable to be vibrated by the belt and by the action of the reciprocating parts of the machine. To overcome this, I provide a locking rod

20 slidably held by the frame 2 and adapted to be moved by the opening of the extension leaf 3, in a manner to engage a fixed ledge 21, its disengagement being effected by a 5 suitable spring, as 22, acting against the head 23 of the rod.

This rod 20 moves with the drop frame 2 as the latter descends to its housing position, and consequently some intermediate 10 and separate member must be provided for receiving the actuating power from the leaf 2 and conveying it to the rod 20. This consists preferably of a pin 24 having a head 25 against which the leaf 2 acts, and a helical spring 26 for moving the pin outwardly. As indicated in Fig. 5, I prefer to have a recess 27 in the head 23 into which the end of the pin enters, in order that this 15 end of the rod 20 shall be supported as well 20 as its other end by the ledge 21.

Thus formed, the opening up of the extension leaf 2 acts to elevate the drop head into operative position, and then to securely lock the drop head against vibration.

25 What I claim is:

1. A sewing machine table having a hinged drop-head frame, a hinged drop leaf, a rod slidably carried by said frame paral-

lel with the axis of its hinges and substantially equal in length to the width of the 30 frame, and a pin slidably supported by the sewing machine table and adapted when the said leaf is swung to its outward operative position to press said rod into engagement with a support provided therefor. 35

2. A sewing machine table having a hinged drop-head frame, a hinged drop leaf, a rod slidably carried by said frame parallel with the axis of its hinges, a pin slidably supported by the sewing machine table 40 to be pressed by said drop leaf toward said rod's adjacent end, a spring normally holding said rod away from said rod, and a support for the end of said rod opposite said pin but normally out of reach thereof, the 45 end of said rod adjacent said pin being recessed for partially receiving said pin, whereby the said drop leaf acts to push said pin into said rod and the opposite end of said rod into the engagement of said support. 50

In testimony that I claim the foregoing invention, I have hereunto set my hand this twenty third day of May, 1922.

LEONARD ATWOOD.
